M. KARP.
CIGARETTE BOX.
APPLICATION FILED OCT. 28, 1915.

1,235,572.

Patented Aug. 7, 1917.

UNITED STATES PATENT OFFICE.

MORRIS KARP, OF PASSAIC, NEW JERSEY, ASSIGNOR TO PASSAIC METAL WARE COMPANY, OF PASSAIC, NEW JERSEY, A CORPORATION OF NEW JERSEY.

CIGARETTE-BOX.

1,235,572.

Specification of Letters Patent. Patented Aug. 7, 1917.

Application filed October 28, 1915. Serial No. 58,405.

To all whom it may concern:

Be it known that I, MORRIS KARP, a citizen of the United States, and resident of Passaic, in the county of Passaic and State 5 of New Jersey, have invented certain new and useful Improvements in Cigarette-Boxes, of which the following is a specification.

Where delicate articles, such as cigarettes 10 and cigars, are placed in containers or boxes in a loose manner, the user must be careful when picking out such articles not to injure the same.

The object of my invention is to provide 15 a container or box with means to cause the contents at one end to be lifted from the bottom of the container in position for ready access by the user when the cover or lid has been opened.

20 In carrying out my invention I provide a container or box having a cover or lid with a movable member within the container or box upon which a portion of the contents may lie when the cover or lid is closed, and 25 means coactive between said member and said cover or lid to cause said member to rise and lift the adjacent ends of articles thereon from the bottom of the container or box in position to enable the ends of said 30 articles conveniently to be grasped.

My invention further comprises novel details of improvement and combinations of parts that will be more fully hereinafter set forth and then pointed out in the claims.

35 Reference is to be had to the accompanying drawings forming part hereof, wherein,

Figure 1 is a perspective view of a container embodying my invention, showing the same in the opened position;

40 Fig. 2 is a cross section on the line 2, 2, in Fig. 1;

Fig. 3 is a detail edge view of Fig. 4;

Fig. 4 is a section on the line 4, 4, in Fig. 3, and

45 Fig. 5 is a detail perspective view of the movable member of the container.

The container or box 1 may be made in any suitable manner, and is shown in the form of a shallow box adapted to contain 50 cigarettes. The cover or lid 2 is hinged to box 1, so as to fold relatively thereto. I have shown the hinge pin or pintle 3 interposed between the hinge members or eyes 4 of the box and cover in an ordinary 55 manner. Within box 1 is a movably sup-

ported member 5, shown extending across the box and adapted to rest upon the bottom of the box, with the articles or cigarettes 6 resting at one end upon said member. Member 5 is shown pivotally supported within 60 box 1 and adapted to be raised by the cover when the latter is opened. For such purpose I have provided coacting parts between member 5 and cover 2. In the form illustrated the member 5 is shown provided with 65 a hinge portion comprising an extension 5^a having an eye 5^b receiving pin or pintle 3, whereby said member is hinged to the box. Cover 2 is shown provided with a projection 2^a adapted to pass through an 70 opening 1^a in the box wall 1^b, that has the hinge members 4. Projection 2^a is adapted to operate member 5 when the cover is opened to cause said member to rise to raise the articles 6 with it.

75 With a container or box embodying my invention, the member 5 will be depressed in the box when the cover is closed, and the articles 6 will rest in the box in an ordinary manner, but certain of their ends 80 will be upon member 5, as illustrated in Fig. 4. When the cover is opened to a sufficient extent, its projection 2^a, by passing through opening 1^a of the box wall, will engage the part 5^a of member 5 and will 85 cause said member to be moved outwardly or upwardly on its hinge, whereby the adjacent ends of articles 6 will be raised from the bottom of the box, as illustrated in Fig. 2, in convenient position to enable the user 90 to apply his finger to the adjacent end of such an article, in order readily to grasp or lift the same out of the box. When the lid is closed member 5 swings down toward the bottom of the box and the articles 6 95 again nest snugly thereon.

95 While I have referred to cigarettes and cigars, for which the container is particularly adapted, it will be understood that the container may be adapted to contain any other desired articles, and has particular reference to containing articles liable to be injured when roughly handled. Although I have illustrated a convenient form of container as a receptacle for cigarettes, it will 100 be understood that changes may be made in the details of construction and arrangements of parts, within the scope of the appended claims, without departing from the spirit of my invention.

Having now described my invention what I claim is:—

1. A container having a pivoted cover, a member within said container adapted to permit articles to rest thereon, means pivotally supporting said member within said container at the same end as the cover, and a projection on the cover to pass through an opening in the container adjacent the pivotal points of both to cause the cover to raise said member and articles thereon by the opening of said cover.

2. A container having a movable cover, a member in said container adapted to permit articles to rest thereon, said member having an extension provided with an eye, a pin carried by said container receiving said eye, said cover being provided with a projection to coact with said extension, said container having an opening for the reception of said projection to permit it to engage said extension when said cover is opened.

3. A container having a wall provided with an opening, a movable cover hinged to said container, said cover having a pro-

jection adapted to pass through said opening, a member within said container adapted to permit articles to rest thereon, said member being pivotally supported by said container and having a portion adapted to be engaged by said projection to raise said member and articles when the cover is opened.

4. A container having a wall provided with an opening, a cover, hinge members supporting said cover upon said container, said cover having a projection adapted to pass through said opening, and a member within said container adapted to permit articles to rest thereon, said member having a hinge portion mounted upon one of the hinge members first named adapted to be engaged by said projection when the cover is opened.

Signed at Passaic, in the county of Passaic, and State of New Jersey.

MORRIS KARP.
